UNITED STATES PATENT OFFICE.

WILLIAM HENRY KIMBERLIN, OF BISMARCK, NORTH DAKOTA.

BOW-FACING OAR.

Application filed November 4, 1926. Serial No. 146,234.

This invention relates to bow facing oars and more particularly to a device of this character in which the blade is feathered.

An important object of the invention is 5 to provide a device of this character which may be very readily and cheaply constructed, which will be durable and efficient in service and a general improvement in the art.

A further object of the invention is to 10 provide a device of this character which may be very readily attached to and removed from the boat, so that loss thereof through theft may be prevented.

A further object of the invention is the 15 provision of a novel and improved feathering mechanism particularly adaptable to bow facing oars.

These and other objects I attain by the construction shown in the accompanying 20 drawings, wherein for the purpose of illustration is shown a preferred embodiment of my invention and wherein:—

Figure 1 is a plan view showing a feathering oar constructed in accordance with my 25 invention applied to the gunwale of a boat;

Figure 2 is a side elevation thereof;

Figure 3 is an enlarged plan view of the 30 plate showing in dotted lines the connection between the levers;

Figure 4 is a section on the line 4—4 of Figure 3 showing the position of the control lug during the working stroke;

Figure 5 shows the operation of the tripping lug when the control lug is moved in 35 the direction of the working stroke while in the feathering position;

Figure 6 is a view showing the manner in which the lug is positioned at the end of the working stroke;

Figure 7 shows the position of the control lug after a short movement on the feathering stroke;

Figure 8 shows the position of the lug 40 when the feathering movement has been completed;

Figure 9 shows the position assumed by the control lug when engaged by the tripping lug at the end of the feathering stroke;

Figure 10 is a view of the adjacent ends 45 of the levers with the top plate removed;

Figure 11 is an enlarged view of the latch employed for holding the feathering oar in position upon the gunwale of the boat;

Figure 12 is a sectional view through the 50 adjacent end of the lever and its mounting;

Figure 13 is a sectional view at right

angles to that shown in Figure 12 illustrating the manner of mounting the oar upon the gunwale.

Referring now more particularly to the 60 drawings, the numerals 10 and 11 indicate upper and lower plates connected by spaced pivot bolts 12 and 13. The lower plate 11 is provided with lugs 11^a, the upper ends of which abut the upper plate to limit movement of the plates toward one another as the 65 nuts 15 of the bolts are tightened. Upon the pivot bolts 12 and 13 are mounted levers 16 and 17, each having flat faces 10^a, 11^a, confronting the plates 10 and 11. Adjacent 70 ends of the levers 16 and 17 interdigitate and are connected by a pin and slot connection 18 through which power may be transmitted to the lever 17 from the lever 16.

The lever 16 is formed in two sections 16^a, 75 16^b, the section 16^a engaging the pivot and having formed in its outer end a socket 19 receiving the end of the sections 16^b. Through the sections 16^a and 16^b, aligned 80 openings 20 and 21 are formed permitting passage of the pivot bolt, so that this bolt serves not only to provide a pivot for the lever 16, but likewise as a means for connecting together the sections thereof. The outer end of the section 16^b has secured thereto in any suitable manner a handle 22. The lever 17 is similarly formed in two sections 17^a and 17^b and the section 17^a is socketed at 23 in its outer end for the 85 reception of the section 17^b. The sections 17^a and 17^b are provided with openings 24 and 25 for the passage of the pivot bolt 13. The outer end of the section 17^b has operatively secured thereto an oar blade 26.

As a means for securing the oar to the 90 sides 27 of the boat, I provide a plate 28 having openings 29 for the passage of securing elements for engagement with the sides of the boat and having vertically extending ears 30. Between the ears 30, a supporting 100 block 31 is mounted for rocking movement upon pivot bolts 32. The upper surface of this supporting block is provided with upwardly extending lugs 33 adapted to project through openings 34 formed in the plates 10 and 11. The upper ends of these lugs immediately above the face of the upper plate 34, when the oar is in position thereon, are formed with horizontally extending slots 35 in their adjacent faces. To 105 the upper plate is pivoted a latch bar 36, the pivot being arranged intermediate the 110

openings, for the passage of the lugs 33 the ends of the bar being adapted to engage in the slots 35, so as to prevent vertical movement of the oar. Flanges 37 upon the plate engage with the lugs and limit the movement of the plate when it is properly engaged in the slots 35.

The connection between the section 17^b of the lever 17 and the blade 26 is in the form of a tube 38, the inner end of which 10 rotatably engages the section 17^b and the outer end of which is forked to receive the blade 26, as indicated at 39. The rotation of the tube upon the section 17^b of the lever 17 is limited through a pin and slot engagement 40 and 41 to 90°, so that the blade may be either placed horizontal or vertical, as desired. A portion of the inner end of the tube projects between adjacent faces 20 of the plates 10 and 11 and upon this portion, the tube is provided with a lug 42 having a flat face 43 which, when the pin 40 is at one end of the slot 41, flatly engages against one of the plates and which serves 25 to prevent rotation of the tube and a second face 44 at substantially right angles to the face 43 which, when the pin is at the opposite end of the slot, engages the plate to prevent rotation of the sleeve in one direction. Since the pin 41 at this time limits 30 rotation of the tube in the opposite direction, the tube is held stationary in each of its two positions and these positions are at right angles to one another. When the tube is in the first named position, the blade is 35 perpendicular and in its operative position and when in the last named position, the blade is horizontally disposed and in what is generally known its feathered position.

In order that by the operation of the lever, the tube and blade may be rotated from one to the other of said positions, I provide in the plate 10, with which the lug 40 coacts, openings 45 and 46 with which the lug of the tube is aligned when the blade 45 is at the ends of its working and feathering strokes, respectively. The tube 38 is provided with a pair of opposed shoulders 47 and 48, circumferentially spaced from one 50 another 90° about the tube and at present disclosed as provided by forming in the tube a slot 49, the opposite end walls of which provide the shoulders. This slot is so disposed that the shoulder 47 is substantially 55 perpendicular to the plate 11, while the oar is on its working stroke, and the shoulder 48 is perpendicular to the plate 11 when the oar is on its feathering stroke. The plate 10 has projecting outwardly from the face 60 thereof lugs 50 and 51 substantially opposing the openings 45 and 46 and adapted for coaction with the shoulders 47 and 48. As the oar arrives at the end of its working stroke, as more particularly illustrated in 65 Figure 6, the lug 50 engages with the shoul-

der 47. Since the oar at this time is moving in the direction of the arrow A of this figure, the tube is rotating in the direction of the arrow B until the binding of the face 43 of the lug against the plate 10 70 limits this movement. This places the nose 52 between the faces 43 and 44 of the lug in the notch 45, so that in return movement, the plate, by its engagement with this nose, rotates the tube to the position shown in 75 Figure 5, where the device illustrated has just begun its feathering stroke. Arriving at the end of its feathering stroke, the lug 51 engages against the shoulder 48, rotating the tube and lug in the opposite direction, so that the nose of the lug is projected into the opening 46. When movement is again reversed, the inner edge of this opening, by its engagement with the face 43, will rotate the lug and tube, so 80 that the face 43 is positioned to slidably engage against the upper surface of the plate 11. It will, of course, be obvious that the rotation imparted to the tube by the edge of the opening 45, during the initial portion 85 of the feathering stroke, will move the slot 49 to a position where the lug 50 could not enter the same if the movement of the oar was checked before the feathering stroke was fully completed and the oar returned 90 upon what is normally the working stroke. In order to prevent the lug 50 from binding against the tube and thus causing damage, I place adjacent the edge of the opening 45 upon the plate 11 a lug 53 which, 100 upon movement of the oar in the direction of the working stroke, but with the tube and blade in the feathering stroke position, engages a shoulder 54 on the tube. This shoulder is at one end of a slot 55 which the 105 upper end of the lug traverses when the oar is in its working stroke and the tube and blade are properly positioned. This lug, by its engagement with the shoulder 54, imparts sufficient rotation to the tube in the direction of the arrow to align the slot 49 for the reception of the lug 50. This lug furthermore serves as a means for providing a short working stroke, as it will be 110 obvious that if the blade is returned before 115 the feathering stroke is completed, the lug will partially turn the blade and the engagement of the blade with the water will complete the turning movement, so that the blade is in its working stroke position for 120 a short distance. Thus, instead of the full working stroke, repeated short working strokes may be produced, if desired. In construction, the pin of the pin and slot connection between the levers is preferably 125 left loose, so that it provides a roller reducing friction between the elements.

It will be obvious that the construction hereinbefore set forth is capable of a certain range of change and modification with- 130

out materially departing from the spirit of the invention and I accordingly do not limit myself to such specific structure except as hereinafter claimed.

5. I claim:—

1. In a feathering oar and in combination, a plate, a lever pivoted to the plate, means for shifting the lever about the pivot thereof, a sleeve rotatably mounted upon the lever and bearing a blade, means limiting rotation of the sleeve at positions where the blade is arranged in the plane of swing and when the blade is perpendicular to the plane of swing of the lever, a lug upon the sleeve having faces coacting with the plate when the sleeve is at said limits of its movement to prevent return movement of the sleeve, means coacting with the tube when the lever is at the opposite limits of its movement for partially rotating the sleeve from one toward the other of said positions, said plate having coaction with said lug during the initial portion of the stroke of the lever completing the rotation of the sleeve from one to the other of said positions.

2. In a feathering oar and in combination, a plate, a lever pivoted to the plate, means for shifting the lever about the pivot thereof, a sleeve rotatably mounted upon the lever and bearing a blade, means limiting rotation of the sleeve at positions where the blade is arranged in the plane of swing and when the blade is perpendicular to the plane of swing of the lever, a lug upon the sleeve having faces coacting with the plate when the sleeve is at said limits of its movement to prevent return movement of the sleeve, means coacting with the tube when the lever is at the opposite limits of its movement for partially rotating the sleeve from one toward the other of said positions, said plate having coaction with said lug during the initial portion of the stroke of the lever completing the rotation of the sleeve from one to the other of said positions, the plate having openings into which the lug extends during such initial movements thereof by the first named means, the edges of said openings by engagement with the lugs completing rotation of the sleeve.

3. In a bow facing oar, spaced plates, spaced pivots extending between the plates, a lever pivoted upon each pivot adjacent the ends of the levers providing interdigitated portions having pin and slot engagement with one another, a blade carried by one of said levers, a handle carried by the other of the levers, one of said plates having lugs engaging the other of the plates to maintain the plates in spaced relation, the pivots maintaining the plates in assembled relation against the lugs.

4. In a bow facing oar, spaced plates, spaced pivots extending between the plates, a lever pivoted upon each pivot adjacent

the ends of the levers providing interdigitated portions having pin and slot engagement with one another, a blade carried by one of said levers and a handle carried by the other of the levers, said levers being each formed in two sections one of which has a socket in which the other fits, the pivot of each lever extending through the walls of the socket of the lever and through the engaged end portion of the outer section of the lever.

5. In a feathering oar and in combination, a plate, a lever pivoted to the plate, means for shifting the lever about the pivot thereof, a sleeve rotatably mounted upon the lever and bearing a blade, means limiting rotation of the sleeve at positions where the blade is arranged in the plane of swing and when the blade is perpendicular to the plane of swing of the lever, a lug upon the sleeve having faces coacting with the plate when the sleeve is at said limits of its movement to prevent return movement of the sleeve, said sleeve having shoulders and lugs engaging said shoulders at the ends of the stroke of the lever for partially rotating the sleeve from one toward the other of said positions, said plate having coaction with said lug during the initial portion of the stroke of the lever completing the rotation of the sleeve from one to the other of said positions.

6. In a feathering oar and in combination, a plate, a lever pivoted to the plate, means for shifting the lever about the pivot thereof, a sleeve rotatably mounted upon the lever and bearing a blade, means limiting rotation of the sleeve at positions where the blade is arranged in the plane of swing and when the blade is perpendicular to the plane of swing of the lever, a lug upon the sleeve having faces coacting with the plate when the sleeve is at said limits of its movements to prevent return movement of the sleeve, means coacting with the tube when the lever is at the opposite limits of its movement for partially rotating the sleeve from one toward the other of said positions, said plate having coaction with said lug during the initial portion of the stroke of the lever completing the rotation of the sleeve from one to the other of said positions; the face of the lug coacting with the plate when the blade is in the last named position flatly engaging the plate to thereby resist rotation of the sleeve under pressure applied to the blade.

7. In a bow facing oar, spaced plates, spaced pivots extending between the plates, a lever pivoted upon each pivot adjacent the ends of the levers providing interdigitated portions having pin and slot engagement with one another, a blade carried by one of said levers, a handle carried by the other of the levers and a horizontally pivoted member upon which the plates are mounted,

said horizontally pivoted member having upwardly projecting pins extending through openings formed in the plate, the upper plate having upon the upper surface thereof intermediate the openings through which the pins extend a pivot for a latch, said latch engaging the slots formed in the upper end of the pin.

8. In a feathering oar and in combination, a plate, a lever pivoted to the plate, means for shifting the lever about the pivot hereof, a blade bearing sleeve rotatable upon the lever from a position where the blade is in working position to a position where the blade is feathered, means positively limiting the pivotal movement of the lever and shifting said sleeve whereby as the lever is moved in one direction the blade is in the working position and in the opposite direction the blade is feathered and means for partially rotating the blade from the feathered toward the working position when the blade is moved in the direction of the working stroke while feathered.
9. In a feathering oar and in combination, a plate, a lever pivoted to the plate, means for shifting the lever about the pivot thereof, a sleeve rotatably mounted upon the lever and bearing a blade, means limiting rotation of the sleeve at positions where the blade is arranged in the plane of swing and when the blade is perpendicular to the plane of swing of the lever, means coacting with the tube when the lever is at opposite limits

of its movement for partially rotating the sleeve from one toward the other of said positions, means upon the sleeve and coacting with the plate during the initial portion of the stroke of the lever for completing the rotation of the sleeve from one to the other of said positions and during the stroke maintaining the sleeve stationary in one or the other of said positions.

10. In a feathering oar and in combination, a pivoted lever swingable between certain limits, a sleeve rotatably mounted upon the lever and bearing a blade, means limiting rotation of the sleeve upon the lever in positions where the blade is arranged in the plane of swing of the lever and when the blade is perpendicular to the plane of swing of the lever, a member adjacent which the lever operates and coacting elements upon the sleeve and member partially rotating said sleeve when the sleeve is at either limit of its movement from one toward the other of said positions and means upon said sleeve coacting with the member preventing rotation of the sleeve while the sleeve is intermediate the limit of its movement and completing the rotation of the sleeve from one toward the other of said positions in the initial movement of the lever after shifting of the sleeve by the first named means.

In testimony whereof I hereunto affix my signature.

WILLIAM HENRY KIMBERLIN.
